CONSUMER TYPE CONTAINER END
STRUCTUREGlenn S. Thompson, Milwaukee, Wis., assignor to
Ira Milton Jones, River Hills, Wis.

Application May 22, 1947, Serial No. 749,751

10 Claims. (Cl. 229—5.5)

1

This invention relates to containers made from flexible sheet material such as paper or fiber board, or any suitable thin flexible sheet metal, and of the type which are adapted to provide inexpensive one-time packages for food products and the like. More specifically this invention relates to consumer type containers such as those illustrated in the patent to Lewis C. Brooks, No. 2,398,404, issued April 16, 1946, and especially like those shown and described in the co-pending application of Lewis C. Brooks, Serial No. 741,904, filed April 16, 1947, now Patent No. 2,589,045.

The containers of the aforementioned patent and co-pending application are characterized by the provision of hollow rims at their ends having the dual function of reinforcing the body and providing rigid closure supporting ledges flush with the ends of the body upon which the end closures may be readily adhered with a fluid tight seal.

Containers made from a single blank of flexible sheet material in accordance with the aforesaid co-pending application, have the hollow closure supporting and reinforcing rim formed from an inwardly folded extension running across the adjacent ends of all but one of the side wall forming panels of the blank with the extreme marginal edge of the inwardly folded extension anchored to the inner surfaces of the side walls. The remaining side wall of the body has a cover flap extension at one or both ends thereof to provide for closing the ends of the body.

In forming up the tubular bodies of such containers, the rims are formed in the flat condition of the blank and after the blank has been folded on the score lines defining the side walls from one another to produce a tubular body, the terminal ends of the rims are adhesively attached to the cover carrying wall in abutting relationship thereto.

One disadvantage of this construction is that there is danger of liquids in the container seeping past the abutting joint between the terminal ends of the rims and the cover carrying wall of the container, such liquid entering the interior of the hollow rim to become trapped therein. This condition is exaggerated, of course, whenever the abutting connection between the ends of the rims and the cover carrying wall breaks loose from rough handling of the filled container.

With these objections to past containers in mind, it is an object of this invention to provide a consumer type container made from a one-piece blank and having means for effectively sealing the ends of the hollow rim at the interior

2

of the container so as to effectively preclude the entry of liquids into the interior of the rim.

A further object of this invention resides in the provision of an improved consumer type container made from a single blank of flexible sheet material and which is fabricated in a manner which precludes leakage of liquids packaged in the container.

With the above and other objects in view, which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate several complete examples of the physical embodiment of the invention constructed according to the best modes so far devised for the practical application of the principles thereof, and in which:

Figure 1 is a fragmentary perspective view of the upper portion of a container constructed in accordance with this invention and looking down at one back corner thereof;

Figure 2 is a longitudinal sectional view through the container of Figure 1 and taken along the plane of the line 2—2;

Figure 3 is a cross sectional view through the container of this invention taken along the plane of the line 3—3 in Figure 2;

Figure 4 is a fragmentary perspective view somewhat similar to Figure 1 but having portions of the back wall and closure broken away to illustrate interior details of construction;

Figure 5 is a plan view of a portion of the cut and scored blank from which the container of Figures 1 to 4 inclusive is made;

Figure 6 is a fragmentary perspective view similar to Figure 1 but illustrating the manner in which the invention is embodied in a three-sided container;

Figure 7 is a plan view showing a portion of a cut and scored blank from which the container of Figure 6 is made;

Figure 8 is a cross sectional view similar to Figure 3 looking at the underside of one end closure for the three-sided container;

Figure 9 is a fragmentary perspective view looking at one terminal end of the hollow rim on the side walls of the container and illustrating a slightly modified manner of closing the ends of the rim;

Figure 10 is a fragmentary perspective view

showing a modified manner of sealing the hollow rim at the junction between the side walls of the container;

Figure 11 is a perspective view of the top portion of the body of a container having a cover supporting rim extending around the entire mouth of the container and illustrating an improved manner of sealing the rim at the corners of the body;

Figure 12 is a plan view of one end of the blank from which the container of Figure 11 is made;

Figure 13 is an enlarged view of a portion of the blank shown in Figure 12; and

Figure 14 is a greatly enlarged detail perspective view of one inside corner of the container of Figure 11 showing the condition of the corner seal for the rim just prior to closing the corner.

Referring now more particularly to the accompanying drawings in which like numerals indicate like parts, it will be seen that Figures 1 to 5 inclusive pertain to a four-sided container made from a single blank of flexible sheet material, such as paper or fibre board. Inasmuch as both ends of the container may be made in identical fashion, only the upper portion of the container has been shown, and it is to be understood that the description, while directed to only the upper end of the container, may apply to its lower end as well.

The four-sided container illustrated in Figures 1 to 5 inclusive comprises a back wall 5 to which are joined three connected side walls 6 in a manner producing a tubular body of substantially rectangular, or more particularly square, prismatic shape.

Referring briefly to Figure 5, it will be seen that the back wall 5 comprises one of the end panels of the blank from which the container is made and that the side walls 6 comprise the three adjacent connected panels of the blank connecting with one side of the end wall forming panel 5 as shown. The other side edge of the end wall forming panel 5 is provided with the customary glue flap 7 which is adhered in overlapped relationship, to the free side edge of the panel 6 at the opposite end of the blank to secure the panels in their tubular body forming position.

The upper end portion 8 of the back wall 5 is shown bent diagonally forwardly from a transverse bend line 9 shaped a distance inwardly of the transverse score line 10 which extends across the three side walls 6 and defines the upper open end of the body. The bend line 9 is, of course, defined by a suitable score on the blank, and the strip 8 is swung forwardly therefrom to lie at an oblique angle to the plane of the back wall 5 as well as to the plane of the adjacent end of the container body. This oblique strip extends transversely across the full width of the back wall 5 and has the cover flap 11 hinged thereto as at 12, it being understood that the hinge line is defined by a suitable score on the blank.

It is important to note that the cover flap, together with the strip 8, is formed as an extension on the end of the back wall 5, and that the strip 8 extends diagonally across the corner defined by the cover or closure 11 and the back wall 5. Also it will be seen that the hinge line 12 lies substantially in the plane of the end of the container body and is parallel to the back wall 5 but spaced a distance forwardly thereof.

The three side walls 6 of the container are 75

provided with a common extension 13 running across the ends thereof. The longitudinal score lines 14 defining the body walls are continued out to the outer edge of the extension, and the extension itself has spaced score lines 15 running entirely thereacross parallel to the score line 10 defining the end of the body. The score lines 15 divide the extension into three adjacent transverse strips, an inner strip 16, an outer strip 17, and an intermediate strip 18.

As described in detail in the aforementioned patent of the applicant and the co-pending application Serial No. 741,904, the extension is bent on the score lines 10 and 15 to dispose the inner strip 16 substantially perpendicular to the side walls 6, with the intermediate strip 18 extending diagonally downwardly between the strip 16 and the inner surfaces of the side wall in which position these strips are rigidly maintained by adhering the outermost strip 17 flatwise onto the inner surfaces of the side walls beneath the strip 18, as shown best in Figure 2.

The intermediate strut-like strip 18 and the outermost anchor strip 17 are unbroken or uncut for their entire length, but substantially triangular notches 19 are cut in the ledge forming strips 16 at the score lines 14 to facilitate bending the blank on these score lines to form up the tubular body of the container. The strip 18, however, is provided with diagonal scoring 20 extending between the scores 15 and converging from the corners of the triangular notches 19 on the innermost score line 15, to a point at the intersections of the outermost score 15 with the vertical scores 14, as seen in Figure 5.

In the forming up of the tubular body, the diagonal scoring 20 on the strip 18 allows the portions thereof at the corners defined by the side walls to be doubled up flatwise upon itself or "pleated" inwardly into the interior of the hollow rim formed by the strips 16, 17 and 18, beneath the flat ledge 16 thereof with the upper free edges of the pleats abutting the underside of the ledge 16; while the triangular cutouts 19 produce abutting mitered joints for the sections of the ledge forming strip 16. In this manner, the ledge 16 extends substantially continuously along the side walls 6, while the strut-like strip 18 and the anchor strip 17 extend uninterruptedly and unbroken around the side walls to preclude leakage of liquids in the container into the hollow rim provided by the inwardly folded strips of the extension 13 at the corners defined by the side walls 6.

The hollow rim thus formed has its terminal ends disposed substantially in abutting relationship with the sloping portion 8 of the back wall, and only the anchor strip 17 and the extreme lower portion of the strut forming strip 18 extend up to the plane of the back wall 5.

The ledge forming strip 16 at the ends of the rim is cut off as seen at 22 in Figure 5, so as to squarely abut the sloping portion 8 of the back wall directly at the hinge 12, while the end portions of the strut forming strip 18 are scored along substantially diagonal lines 23 similar to the scoring 20 so that the extreme ends 24 of the strip 18 outwardly of the scores 23, when bent inwardly away from the rim (along the scores 23) allow the end portions of the strut forming strip to likewise abut the slanting portion 8 of the back wall 5.

The ends 24 of the strut forming strip 18 provide flaps, which when bent out from the terminal ends of the hollow rim, lie flatwise against

the inner surface of the slanting portion 8 of the back wall and extend the full distance between the bend lines 9 and 12 defining the sloping portion 8 of the back wall so that when adhered in this position, the flaps not only join the wall portion 8 to the ends of the rim but also effectively seal off the terminal ends of the hollow rim from the interior of the container.

The opposite ends of the anchor forming strip 17 are likewise provided with flaps 27 bent from scores 28 on the strip at the plane of the back wall 5. These flaps 27 overlie the inner surfaces of the back wall 5 beneath or inwardly of the slanting end portion 8 thereof and when adhered flatwise thereto as shown best in Figure 2 provide additional assurance against leakage of liquids past the joint between the rim and the back wall and into the terminal ends of the rim.

It should be noted that at the end of the extension 13 adjacent to the back wall 5, the flap 27 on the anchor strip 17, as well as a portion of the flap 24 on the strut forming strip 18 is formed from stock cut from the cover flap 11, which is accordingly notched out as at 29 for this purpose. The bottom of the notch 29, however, lies intermediate the side edges of the ledge 16 therebeneath so that there is sufficient overlapping of the cover on the ledge at the notch to effect proper sealing of the closure.

Inasmuch as the container when intended for packaging milk or other liquids has all of its surfaces coated with paraffin or some other adhesive coating capable of being activated to adhesive-ness by the application of heat and pressure to the overlapped or joining parts, it will be apparent that the sealing of the closure 11 upon the ledge 16 of the rim by the application of heat and endwise pressure onto the container effectively seals the end of the container and precludes entry of liquid in the container into any portion of the hollow rim.

Still further assurance against leakage of liquids past the terminal ends of the rim may be had by bending the flap-like corners 30 on the side walls adjacent to the terminal ends of the hollow rim over onto the exterior surface of the diagonal end or strip 8 on the back wall as seen in Figures 1 and 4, and adhering these flaps thereto in the position shown so as to, in effect, clamp the end portions of the strip 8 between them and the inner flaps 24 on the strut forming strip 18. Attachment of the flaps 30 to the sloping end 8 of the back wall also reinforces the connection between the sloping end 8 and the ends of the hollow rim to preclude the ends of the rim pulling away from the back wall under rough handling of the container.

Although the container shown in Figures 6, 7 and 8 is of substantially triangular prismatic form, the essential features of the previously described container are embodied therein. The back wall 5' in this case likewise has the cover flap 11' formed as an integral extension of the end thereof; the two side walls 6' which connect with the back wall 5' likewise have a hollow rim at the end of the container formed by an extension 13' on the side walls; and flaps 24' and 27' on the terminal ends of the rim likewise fold over onto the inner surface of the sloping wall portion 8' on the back wall to close the ends of the rim and join the same to the back wall of the container. Side wall flaps 30' may also be adhered to the exterior surfaces of the wall portion 8' to provide additional assurance against leakage of liquids past the terminal ends of the rim.

In this embodiment, however, it is to be noted that the body of the closure 11' is substantially triangular in shape to fit the end of the container, and has flanges 35 bent downwardly from its side edges to overlie and be adhered to the side walls 6' as seen in Figure 6 to reinforce the connection of the closure to the ledge on the side walls.

In this case also the body of the closure is preferably provided with a transverse score line 36 parallel to the back wall 5' and leading to the flanged edges of the closure to provide a hinge upon which the forward portion of the closure may be lifted to thereby uncover a pouring opening at the top of the container. Slits 37 leading downwardly from the ends of the score line 36 to the free side edges of the flanges facilitate lifting of the forward portion of the closure when it is desired to dispense the container contents.

In both embodiments described, the flaps on the strut member have been bent toward the interior of the container, away from the rim on the side walls, but Figure 9 shows a condition where the flaps 40 on the strut member at the terminal ends of the hollow rim are triangular and shaped to fit over the open ends of the rim. This of course involves bending the flaps 40 outwardly to positions with their top edges 41 resting against the ends of the ledge 16 so that the flaps are located between the ends of the rim and the sloping portion of the back wall at the adjacent end of the container.

With the flaps 40 overlying and supported by the ends of the rim, it is only necessary to exert heat and pressure on the sloping portion of the back wall in line with the hollow rim for securement of the sloping wall portion thereto. This assumes, of course, that a suitable adhesive activated by heat and pressure has been applied to the contacting surfaces involved.

Securement of the end closure onto the ledge 16 then securely seals the joint between the upper portion of the flaps and the ledge in an obvious manner, and the end seal is completed and reinforced by adhering the flaps 42, which correspond in all respects to the flaps 30 and 30', in place on the exterior of the sloping portion of the back wall.

Another highly effective manner of precluding leakage of liquids into the hollow interior of the rim at the corners defined by the side walls of the container is illustrated in Figure 10. As here shown, both the ledge 16 and strut forming strip 18 have pleated portions 45 and 46 respectively provided by suitable diagonally extending scores similar to the scores 20 seen in Figure 5. Hence, there is no necessity for notching the ledge, as the provision of a slit along the upper edge of the strut forming strip 18 separates the two pleated portions from one another.

In forming up the container built in accordance with the Figure 10 disclosure, the pleated portions 45 on the ledge 16 are tucked downwardly into the hollow rim as the side walls are brought to their proper angular positions relative to one another to produce mitered corners on the ledge, while the pleated portions 46 are displaced inwardly into the container away from the rim to bring the two halves of the pleat flatwise together, in which condition they may be adhered together in any desired manner. It will also be seen that the flatwise overlapping sections of the pleat 46 may be swung against one surface of the strut-like element adjacent thereto and adhered to the same.

Figures 11 to 14 inclusive illustrate another manner of closing the hollow rim at the end (or

ends) of the container body to preclude seepage of liquid in the container into the interior of the rim. As here shown, the hollow rim extends around all of the side walls of the body to provide a substantially continuous supporting ledge upon which a separate flat end closure disc may be adhered. The rim in this case is likewise formed from a transversely scored extension 50 extending across the side wall forming panels at one end (or both) of the body blank and bent inwardly in the manner heretofore described.

While the cover flap indicated at 51 in construction lines may be formed as a separate disc, it is also desired to point out that the cover may be formed as an extension on the end of an extra side wall forming panel on one end of the blank from which the body is made overlapped on the exterior of the panel at the opposite end of the blank in the same manner as in the attachment of the ordinary glue flap. This latter one-piece construction is illustrated and claimed in the aforementioned copending application, Serial No. 741,904 and forms no part of this application.

The feature of the container made in accordance with Figures 11 to 14 inclusive resides in an improved manner of sealing the hollow rim against seepage of liquids thereinto at the corners of the body defined by the respective side walls thereof. For this purpose, the strut-like strip 52, which extends diagonally between the inwardly directed ledge 53 and the inner surfaces of the side walls for attachment thereto by the anchor strips 54, is likewise provided with pleat forming scores 55 which run divergently from the points of intersection between the outermost scores 15' and the vertical scores 14' to the innermost score 15' and preferably terminate just short of this innermost score of the extension as shown, equidistant from the scores 14'.

From Figure 13 it will be seen that the innermost scores 15' do not extend across the vertical scores 14' but run up to and preferably terminate just short of the divergent ends of the scores 55.

The ledge forming strip 53 of the extension 50, however, has substantially triangular cutouts 56 therein at the scores 14' to facilitate folding of the hollow rim in the forming up of the tubular body to its assembled position seen in Figure 11.

The cutouts 56 have one apex 57 thereof at the points of intersection between the score lines 10' which define the end of the body and vertical scores 14', and the other two corners 58 of each of the cutouts lie adjacent to the divergent ends of the scores 55 on the strut forming strip 52 but are disposed wholly on the ledge forming strip 53 so that their apexes are spaced inwardly of the innermost score 15'.

The side of each of the cutouts adjacent to the innermost score 15' is formed by a pair of equal length cuts 59 which extend outwardly at a wide divergent angle to the corners 58 of the cutouts substantially from the points of intersection between the innermost score 15' and the vertical scores 14', as seen in Figure 13, and these cuts define the top edges 59' of each of the halves of the pleats which result from the scores 55 and that portion of the vertical scoring 14' included between the scores 55.

After bending of the extension 50 back upon itself and securement of the anchor strip 54 to the inner surface of the body side walls in its position maintaining the ledge and strut-forming strips 53 and 52 respectively in their hollow rim producing condition, the pleats defined by the scores 55 and the portions 14' of the vertical

scores included therebetween may be readily folded together and tucked inwardly toward the corners of the body during the act of folding the body side walls along the scores 14' to produce a body of tubular shape. The two halves 60 of the pleats thus fold flatwise together at the junctions of the side walls, as seen in Figure 11, and it is to be noted that the top edges 59' of the flatwise engaged sections of the pleats 10 lie in the plane of the upper exposed surface of the ledge 53.

The widely diverging cuts 59 of the triangular cutouts which define the top edges of the pleats on the strut-forming strip 52 are necessary in 15 order that these edges of the pleats lie in the plane of the exposed surface of the ledge 53 for it will be readily appreciated that the edges of the pleats at the vertical score lines 14' tend to lift up during the operation of tucking the pleated portions inwardly toward the corners of the body.

It will be seen that inasmuch as the apexes of the corners 58 of the cutouts 56 lie inwardly of the innermost score 15', these apexes will lie wholly on the ledge 53 at locations intermediate 25 the side edges of the ledge in the finished container.

Inasmuch as the top edges 59' of the pleats extend only part way toward the extreme corners of the body, the sides of the triangular cutouts 30 56 defining their apexes 57 are formed to close up and produce a mitered joint between the ends of the various sections of the ledge, as seen in Figure 11.

In order to prevent buckling of the ends of the 35 ledge sections when heavy stock is used, however, the sides of the cutouts adjacent to the top edges of the folded together pleats are relieved or notched slightly as at 62 an extent such that the bottom of the notches engage the opposite sides 40 of the folded together pleat when the corners are closed to substantially hold the pleat sections clamped together. Obviously, if the stock from which the container is made is thin enough, the notches 62 are unnecessary.

With this form of corner pleating, it will be 45 seen that the strut-like strip 52 which supports the inner edges of the ledge 53 is unbroken for its entire length, and that the application of the cover 51 flatwise onto the ledge 53 by means 50 of a suitable adhesive thoroughly seals the rim against seepage of liquids thereinto at the corners of the body by its direct engagement with the top edges 59' of the folded together pleats; and by the fact that the cover closes the only 55 possible points at which leakage into the interior of the hollow rim may occur, and which points constitute the corners of the triangular cutouts all of which are disposed on the flat ledge 53 beneath the cover.

The corner seal described is, of course, applicable to containers such as those illustrated in the previous embodiment of the invention and may be used advantageously in such containers at the corners defined by the side walls thereof 60 in place of the pleated portions therein shown.

Referring again to Figure 13 it will be seen that the opposite ends of the strut and ledge forming strips 52 and 53 respectively on the extension 50 are scored and notched so as to provide free substantially triangular flaps 60' on the strut which may be bent toward the glue flap corner of the body and adhered flatwise together in a position closing the ends of the rim in the same manner as the intermediate pleated portions so as to assure a leak-proof joint between

the ends of the hollow rim. The top edges of the flaps 60' also lie in the plane of the exposed surface of the ledge so that the cover is enabled to effect leak proof sealing of the rim at the glue flap cover of the body.

From the foregoing description taken in connection with the accompanying drawings, it will be readily apparent that this invention provides a substantially leak-proof container of relatively great strength and admirably suited for packaging liquid goods.

I claim:

1. In a consumer type container made from flexible sheet material: an upright tubular body including a number of connected flat side walls joined with a relatively flat back wall; a closure for one end of the body flatwise engaged with the adjacent ends of said side walls in perpendicular relationship thereto; means hingedly joining the closure to said back wall including a strip formed from a part of the back wall extending transversely thereacross at said end of the body and bent obliquely to the planes of the closure and back wall so as to lie substantially diagonally across the corner defined by the closure and the back wall; a hollow closure supporting rim carried by and overlying the inner surfaces of the side walls at said end of the body and extending continuously along said side walls to terminate in abutting relationship with said oblique strip on the back wall, said rim including a relatively flat ledge flush with said end of the body and upon which the closure is flatwise adhered, and a strut-like element connecting diagonally between the ledge and the inner surfaces of the said walls and extending without break around the side walls to prevent leakage of liquid in the container into the hollow interior of the rim at the corners defined by said side wall and flaps bent from said strut-like element at the terminal ends of the rim and flatwise adhered to the inner surfaces of said oblique strip on the back wall so as to effectively preclude entry of liquid into the terminal ends of the hollow rim.

2. The container set forth in claim 1 wherein both the closure and the oblique strip connecting therewith are formed as an integral extension of the back wall.

3. The container set forth in claim 1 wherein in the closure and said oblique strip are formed as an integral extension of the back wall of the body, and wherein the juncture between the oblique strip and the closure provides a hinge for the closure substantially on a level with said ledge directly adjacent to the terminal ends of the hollow rim.

4. The structure set forth in claim 1 further characterized by the provision of flaps on the body side walls bent therefrom and flatwise adhered to the exterior surfaces of the opposite end portions of said oblique strip for reinforcing the connection of said oblique strip to the terminal ends of the hollow rim.

5. In a consumer type container made from flexible sheet material: an upright tubular body including a number of connected flat side walls joined with a relatively flat back wall; a closure for one end of the body comprising an extension on said back wall flatwise engaged with the adjacent ends of said side walls in perpendicular relationship thereto, a transversely extending strip on the back wall at said end of the body being bent obliquely forwardly toward the interior of the body and terminating at the plane of the

closure to provide a hinge for the closure parallel to said back wall but spaced forwardly from the plane thereof and substantially on a level with the plane of said end of the body; a hollow closure supporting rim on said end of the body formed from inwardly folded extensions on said ends of the body side walls, said rim extending continuously along the side walls and terminating in abutting relationship with said oblique strip on the back wall, and said rim including a relatively flat ledge upon which the closure rests, and a strut-like strip connecting substantially diagonally between said ledge and the inner surfaces of the side walls to support the ledge and consequently the closure, said strut-like strip being unbroken for its entire length so as to preclude leakage of liquid in the container into the hollow rim at the corners of the container defined by said side walls; and flaps integral with the ends of the strut-like strip bent therefrom and adhered flatwise onto the inner surface of said oblique strip on the back wall so as to close the hollow interior of the rim at the inside of the container adjacent to the terminal ends of the rim.

6. The structure set forth in claim 5 further characterized by the provision of flaps formed as part of the side walls folded over and adhered onto the exterior surface of said oblique strip on the back wall whereby the portions of the oblique strip adjacent to the terminal ends of the rim are substantially clamped between said last named flaps and the flaps on the strut-like strip to preclude leakage of liquids past the joint between the oblique strip and the terminal ends of the rim.

7. In a consumer type container made from flexible sheet material: an upright tubular body having a pair of connected side walls joined with a back wall to give the body a substantially triangular prismatic form, said back wall including a strip extending transversely thereacross at one end of the body bent diagonally forwardly

45 from a bend line parallel to the plane of said end of the body but spaced a distance inwardly thereof; a closure joined to said diagonal strip and flatwise engaged with the adjacent ends of said side walls to close said end of the body; a hollow closure supporting rim carried by and overlying the inner surfaces of said side walls beneath the closure and extending continuously along the side walls to terminate in abutting relationship with said diagonal strip on the back wall, said rim including a relatively flat ledge flush with said end of the body and upon which the closure is flatwise adhered, and a strut-like element connecting diagonally between the ledge and the inner surfaces of the side walls and extending along the same without break to prevent leakage of liquid in the container into the hollow interior of the rim at the corner defined by said side walls; and flaps bent from said strut-like element at the terminal ends of the rim and flatwise adhered to said diagonal strip on the back wall so as to preclude entry of liquid in the container into the terminal ends of the hollow rim.

8. The container set forth in claim 7 wherein said diagonal strip is formed by the end portion of said back wall at said end of the body, and wherein the closure for said end of the body comprises an extension on said diagonal strip integral therewith.

9. The structure set forth in claim 7 further

characterized by the provision of flanges on the closure bent from the side edges thereof and flat-wise adhered to the exterior surfaces of the side walls to reinforce the connection of the closure thereto.

10. The structure set forth in claim 9 wherein said closure is characterized by the provision of a score in the flat surface thereof extending entirely thereacross between the flanged edges of the closure, and wherein said flanges have slits cut therein leading from the free edges thereof to the ends of said score to facilitate lifting the portions of the closure forwardly of said score in the provision of a pouring opening at said end of the container.

GLENN S. THOMPSON.
